DISCHARGE LAMP

Carl P. Brockway, Paramus, N. J., assignor to
 National Television Corporation, Wilmington,
 Del., a corporation of Delaware

Application October 28, 1932, Serial No. 639,973

6 Claims. (Cl. 176—122)

This invention relates to discharge lamps and particularly to that type of discharge lamp for producing modulated light.

One of the objects of the invention is to provide a discharge lamp in which a continuous ionization of the gas is maintained during the operation of the lamp.

Another object of the invention is to provide a discharge lamp in which the discharge is prevented from being extinguished due to heavy modulations in the operating current.

Another object of the invention is to provide a discharge lamp in which the discharge is shifted from one path to another by the modulating current.

Still another object of the invention is to provide a discharge lamp with a plurality of elements so arranged that the useful discharge will occur between two of the elements while a non-useful discharge will occur between another two.

Other objects of the invention and objects relating particularly to the method of assembling and constructing the various parts will be apparent as the description proceeds.

Several embodiments of the invention have been illustrated in the accompanying drawings, in which:

Fig. 1 is a sectional side elevation view of a lamp illustrating one form of the invention which may be preferred;

Fig. 2 is a front elevational view of the lamp of Fig. 1;

Fig. 3 is a fragmentary sectional view of the cathode of Figs. 1 and 2;

Fig. 4 is a sectional side elevational view of a lamp illustrating a different form of the invention;

Fig. 5 is a front elevational view of the lamp of Fig. 4;

Fig. 6 is a sectional side elevational view of a modified form of the lamp of Fig. 1;

Fig. 7 is an enlarged sectional view of a portion of the cathode of Fig. 6;

Fig. 8 is a front elevational view of the lamp shown in Fig. 6;

Fig. 9 is a circuit diagram showing another manner of connecting the lamp of Figs. 6, 7, and 8; and

Fig. 10 is a side elevational view of another form of lamp embodying the invention.

Referring now more specifically to the drawings, the invention is shown in Fig. 1 as comprising an envelope 10 of glass or other suitable transparent material having a neck 11 which is fused to the usual inturned press 12 for sup-

porting the various elements of the device. A pair of solid cathodes 13 and 14 are mounted in approximately the center of the envelope and spaced from each other. These cathodes may be made of any suitable refractory metal such as tungsten, molybdenum, tantalum, iron, or even softer metals, such as nickel and copper. As indicated, they are flat plates somewhat oval in shape and arranged parallel to each other although electrically separated. Any suitable means may be used to mount the cathodes as by means of the support rod 15 which may be welded to the cathode 13 at the bottom thereof, and the support rod 16 which may be welded to the lower end of the cathode 14. The support rods 15 and 16 may be sealed in the press 12 in a well known manner and lead-in wires 17 and 18 may be connected respectively to them for making the outside connection for the lamp.

The cathode 13 may have a hole 19 extending therethrough, positioned on the central line of the cathode but somewhat above the exact center thereof. In like manner the cathode 14 may have a hole 20 positioned on the central axis but below the exact center thereof so as to be out of alignment with the hole 19 and the cathode 13.

An anode 21 having a shape similar to the cathode 13 although lighter in weight and composed, if desired, of a similar metal, may be mounted on a support rod 22 as by welding, and the support rod may be sealed in the press 12 spaced from the support rod 15 as indicated. A lead-in wire 23 may be attached to the support rod 22 for making the external connection to the anode 21. At a point aligned with the hole 19 in the cathode 13 I provide a somewhat smaller hole 24 in the anode so that the hole 19 in the cathode 13 may be viewed through the hole in the anode.

A second anode 25 may be positioned in like manner spaced slightly from the cathode 14. This anode is also about the same size and shape as the cathode 14, although it may be formed of somewhat lighter material, and is mounted upon a support rod 26 which is sealed in the press 12. A lead-in wire 27 may be connected to the support rod 26 for making the external connection. The anode 25 may also be provided with a hole 28 which is in alignment with the hole 20 in the cathode 14.

Both cathodes 13 and 14, and the anodes too, if desired, may be coated with a material 29, which is relatively low in electron emission so as to eliminate or cut down as far as possible the

electron emission from the surface of the cathode, except in the interior of the holes 19 and 20 where the material is omitted. This material may be any suitable insulating material, or 5 if desired, the cathodes may be coated with lamp black, or otherwise carbonized, carbon having apparently the effect of cutting down electron emission to a minimum.

With the elements mounted as described above, 10 the envelope may be connected to a vacuum pump and an oven placed over it to raise the temperature thereof together with the enclosed elements so as to drive out all occluded gases from the elements and envelope. When the parts have 15 been thoroughly freed from gases in a manner well known in the art, a suitable ionizable gas may be admitted to the envelope at a relatively low pressure so as to permit a discharge forming between the anodes and cathodes when a 20 suitable potential is applied between them. This gas may be one of the monatomic gases, such as neon, argon, helium, krypton, and xenon, or mixtures of such gases, and under certain conditions where it is desired to increase conductivity or to produce color effects, metal vapors 25 may be added, such as the vapors of mercury, caesium, sodium, rubidium, and the like. The pressure of the gas should be under 15 mm. of mercury and probably best results are obtained 30 with pressure in the neighborhood of 5 mm.

If one of the cathodes and its adjacent anode are connected to a source of modulated current at a suitable voltage, it will be evident that a discharge will form between the cathode and anode 35 and will concentrate in the hole provided in the cathode which will then act as a crater, and this discharge can be observed through the hole in the anode which may then act as a frame to limit the size of the light source to a predetermined dimension.

I may, however, prefer to connect the lamp in a different manner as clearly indicated in Fig. 1. Here the two cathode leads 17 and 18 are connected by means of wires 30 and 31 respectively to the terminals 32 and 33 of an incoming 45 source of modulated current such as that produced by a television signal or a sound program picked up by a microphone. A wire 34 is connected to both wires 23 and 27 which form the 50 two anode leads and is connected through a battery 35 to a neutral point of the modulated circuit by means of a resistance 36 which is placed across the wires 30 and 31 and to the center of which the negative side of the battery 35 is connected. In a typical set-up a battery voltage of 55 200 volts is employed to initiate the discharge between the cathode and anode with a current ranging from 60 to 120 milliamperes.

As the incoming current fluctuates due to the 60 modulations received, the polarity of the cathodes 13 and 14 will change, one always being more negative than the other depending on the strength of the modulation. As the two anodes 21 and 25 are connected together, their potential 65 will be the same and hence a discharge will form between one of the anodes and whichever cathode has a more negative potential. This discharge is caused by the battery 35 which furnishes a constant source of potential and hence 70 there will be a discharge somewhere in the lamp at all times. However, as the cathode 13, for instance, varies its potential from a low negative towards the positive side, the discharge between the anode 21 and cathode 13 will fall off while 75 that between the anode 25 and the cathode 14

will increase. Hence, while there will always be a discharge in the lamp due to the direct current of the battery 35, that discharge will flicker between the hole or crater 19 in the cathode 13 and the hole or crater 20 in the 5 cathode 14. When the discharge is at the cathode 14, the cathode 13 appears dark, and when it occurs between the cathode 13 and the anode 21, the crater in the cathode 13 appears lighted with an intense illumination. Only the one 10 cathode is therefore used for giving the modulated light although both are adaptable for use and may be used, if desired.

In Figs. 4 and 5 another modification of the invention is illustrated. Here an envelope 10 is 15 provided with an inturned press 12 in which are sealed three support rods 42, 43, and 44. Upon the support rod 42 I position a cathode 45 which is formed of a solid plate of suitable metal having an extended portion 46 on one side and a 20 hole or crater 47 on the other side extending into the portion 46. This cathode may be coated similarly to those described above with a coating 48 of carbon or other suitable material to cut down emission except in the crater 47. The cathode 25 45 and support rod 42 are so positioned that they occupy a plane spaced somewhat from the center of the lamp.

In approximately the center of the lamp I position a small anode 49 upon the support rod 43. 30 This anode may be semi-circular in shape, if desired, and may be formed of the same metal as the cathode 45. A shallow crater 50 is provided in the anode 49 in alignment with the crater 47 of the cathode 45, and the whole anode together 35 with the support rod may be coated with the coating material.

A second and larger anode 51 having a shape similar to the cathode 45 may be positioned spaced slightly on the other side of the anode 49 40 and an opening 52 may be provided in the anode just above the upper edge of the anode 49. Lead-in wires 53 and 54 may be connected respectively to support rods 42 and 43 and a battery 55 or other source of constant potential may be connected across these two wires with the positive side of the battery connected to the anode 49 and the negative side to the cathode 45. A lead-in wire 56 may also be connected to the support rod 44 and anode 51 and may be connected to the 50 terminal 57 for the incoming modulated current while the other terminal 58 of the incoming circuit may be connected by means of a wire 59 to the negative side of the battery 55.

With this construction as indicated in Fig. 4, a 55 direct current discharge will flow between the cathode 45 and the anode 49. This discharge will be concentrated in the crater 47 of the cathode and will not be visible from the front or righthand side of Fig. 4 as it will be obscured 60 by the anode 49. When the anode 51, however, becomes highly positively charged due to the modulating current, the potential of which should be greater than that of the battery, the discharge will leave the anode 49 and pass over the top 65 thereof to the anode 51 so that it may be clearly viewed through the hole 52 in the anode. There will always be a discharge in the lamp and hence 70 there will be no necessity of building up a high starting potential for the modulated current as the discharge will jump to the anode 51 immediately the potential of the anode is higher than 75 that of the anode 49 and instantaneous modulation of the light as viewed through the hole 52 in the anode 51, will, therefore, be evident.

A modified form of the construction of Figs. 1 to 3, has been illustrated in Figs. 6, 7 and 8. Here an envelope 10, provided with the usual press 12, supports a single large solid cathode 62 and a 5 pair of anodes 63 and 64 spaced one on each side of the cathode.

The cathode may be formed of any of the metals mentioned above but is preferably somewhat thicker than either of the cathodes of Fig. 1 10 and may be supported on two support rods 65 which are sealed at the center of the press 12 and which pass upwardly, one on each side of the cathode. The cathode 62 has a crater 66 in one side thereof positioned above the center of the cathode while a crater 67 in the other side of the cathode is positioned below the center, these craters taking the place of the two craters 19 and 20 in the cathodes 13 and 14 of Fig. 1. The cathode 62 may be covered with a coating 68 of the material 20 low in electron emissivity which has already been described. The anode 63 may be provided with an opening 69 in alignment with the crater 66, while the anode 64 has an opening 70 in alignment with the crater 67. The anodes 63 and 64 25 may be mounted respectively upon support rods 71 and 72 sealed in the press. A lead-in wire 73 may be connected to one of the cathode support rods 65 while lead-in wires 74 and 75 may be connected respectively to the support rods 71 and 72. 30 The lamp may be provided with the gases as described above.

One way of connecting up the lamp just described is indicated in Fig. 6 where a battery 76 has its negative end connected by means of the 35 wire 77 to the lead-in wire 73 for the cathode, while the positive side of the battery is connected by means of a wire 78 to the mid-point 79 of a resistance 80 connected across the two leads 74 and 75 which may be connected respectively to the terminals 81 and 82 of the incoming modulated current circuit.

The lamp functions similarly to that shown in Fig. 1 although opposite thereto. The cathode 62 is given a negative potential by the battery 45 while the two anodes are connected to the modulating circuit so that they vary in potential in accordance with the modulations received. Whichever anode is, therefore, the more positive at the moment will receive the discharge caused by the battery. Hence there will always be a discharge in the lamp but it will flicker between the crater 66 and anode 63 and the crater 67 and anode 64. The intense discharge appearing in either of the craters 66 and 67 may be viewed 50 in front of their respective anodes through the holes 69 and 70 respectively.

In Fig. 9 is shown another means of connecting up the lamp of Fig. 6. Here the cathode 62 is connected by means of a wire 83 to an input terminal 84 of the incoming modulated circuit, while 60 the anode 63 is connected by means of a wire 85 to the other terminal 86 of the incoming circuit. The other anode 64 is connected by means of a wire 87 to the positive side of a battery 88 while 65 the negative side of the battery is connected by means of the wire 89 to the wire 83 connected to the cathode. Thus a constant discharge takes place between the cathode 62 and the anode 64 which tends to maintain an ionized condition of 70 the gas within the envelope and permits the ready formation of discharge between the cathode and anode 63 and maintains it in spite of heavy modulation with long dark periods.

In Fig. 10 still another form of the invention is 75 illustrated in which a pair of glass envelopes 90

and 91 are connected together by a relatively long tube 92, the tube being fused to the glass bulbs at the tip ends thereof so as to form a gas-tight duct between them. The bulb 90 may be provided with a press 93 in which is sealed a support wire 5 94, and an anode 95 consisting of a disc of suitable metal may be secured as by welding to the end of the rod 94. A lead-in wire 96 may be connected to the support rod 94 and may have its other end attached to the terminal 97 of the 10 incoming modulated current circuit.

The bulb 91 may contain a pair of electrodes 98 and 99 mounted in a spaced position upon support wires 100 and 101 respectively. The support rods are sealed in the press 102 which is fused to the 15 envelope as indicated. The electrodes 98 and 99 may be formed of any suitable metal as mentioned above and may be circular in form with the edges thereof terminating not far from the opening of the tube 92. A lead-in wire 103 may be 20 connected to the support rod 100 and have its other end connected to the terminal 104 forming the other terminal of the incoming modulated current circuit. Also a lead-in wire 105 may be 25 connected to the support rod 101 and may be connected to the positive side of a battery 106 whose negative side is connected by means of the wire 107 to the wire 103, or, in other words, to the electrode 98. This puts a constant potential between the electrodes 98 and 99 with the result 30 that a constant discharge will form in the bulb 91. The negative side of the modulated circuit is connected by the wire 103 to the electrode 98 which therefore forms the cathode for the anode 95 and a modulated discharge will form in the 35 tube 92. Inasmuch as the discharge between the plates 98 and 99 is continuous and constant, there will always be ionization in the bulb 91, and hence the discharge can readily start between the electrode 98 and the anode 95, thus creating a practically instantaneous response to modulated 40 input currents.

From the above description it will be seen that I have provided a lamp for use with modulated current in which the ionization in the lamp is 45 maintained constant so that the discharge can start at relatively low voltages and is prevented from being extinguished due to long dark periods in the modulated circuit and current. The lamp lends itself particularly to use with television apparatus in which the modulations are extremely rapid or may also be used in connection with sound-on-film apparatus or in any other instance where modulated light is necessary or desirable. 55

Many modifications of the invention may be resorted to without departing from the spirit thereof, and I do not, therefore, desire to limit myself to what has been shown and described except as such limitations occur in the appended claims. 60

What I desire to secure by Letters Patent and claim is:

1. In combination, a discharge lamp comprising a pair of electrodes, means to connect a modulated circuit to said electrodes, means to create a 65 neutral point between said electrodes, a third electrode within said lamp, a circuit connection between the neutral point and said third electrode and means for impressing a constant potential on said circuit connection, said electrodes 70 being so arranged that the intense discharge between said third electrode and one only of the other electrodes is observable from a given position.

2. In an apparatus of the class described, a 75

- pair of spaced electrodes, an ionizable gas surrounding said electrodes, means to connect a source of modulated current across said electrodes, means to locate approximately the electrical center between said electrodes, a third electrode spaced between said other two electrodes, a circuit connection between said third electrode and electrical center, and means to impress a constant potential upon said circuit connection.
- 5 3. A discharge lamp comprising a pair of closely spaced cathodes electrically separated from each other, an anode spaced from one cathode, an anode spaced from the other cathode, and an ionizable gas surrounding said cathodes and anodes, said anodes and cathodes being so arranged that the intense discharge between one only of said cathodes and one only of said anodes is visible from a given position.
- 10 4. A discharge lamp comprising a pair of flat cathodes with spaced and adjacent faces, a crater in each of said cathodes, said craters being out of alignment, an anode positioned adjacent one of said cathodes, an anode positioned adjacent the other of said cathodes, and an ionizable gas surrounding said
- 15
- 20
- 25

rounding said anodes and cathodes, said anodes being external to said cathodes.

5 5. A discharge lamp comprising a pair of flat cathodes with spaced and adjacent faces, a crater in each of said cathodes, said craters being out of alignment and directed outwardly, an anode positioned adjacent one of said cathodes, an anode positioned adjacent the other of said cathodes, said anodes having openings therein arranged in alignment with the craters of the adjacent 10 cathodes, and an ionizable gas surrounding said anodes and cathodes, said anodes being external to said cathodes.

6. A discharge lamp comprising a pair of flat cathodes with spaced and adjacent faces, a crater 15 in each of said cathodes, said craters being out of alignment, a coating of material having a low electron emission on each of said cathodes with the exception of the craters thereof, an anode positioned adjacent one of said cathodes, an anode 20 positioned adjacent the other of said cathodes, and an ionizable gas surrounding said anodes and cathodes, said anodes being external to said cathodes.

CARL P. BROCKWAY. 25
